UNITED STATES PATENT OFFICE.

PETER JEPSEN, OF WORCESTER, MASSACHUSETTS, ASSIGNOR TO THE AMERICAN STEEL AND WIRE COMPANY OF NEW JERSEY, A CORPORATION OF NEW JERSEY.

APPARATUS FOR ELECTROGALVANIZING.

Application filed February 9, 1927. Serial No. 166,922.

This invention relates to apparatus for electro-galvanizing, and while not limited thereto, relates more particularly to apparatus for electro-galvanizing wire and similar articles of manufacture.

Heretofore it has generally been the practice to mount the anodes and pig zinc in the bottom of the deposition tanks and to pass the articles to be galvanized through the solution above the anodes and zinc, and to constantly turn the articles so as to provide an even coating on all sides of the articles.

When coating wire in the tanks as heretofore constructed it was necessary to twist or turn the wire while it was being moved through the electro-galvanizing tank so as to evenly coat the wire, thus slowing up the operation and at best providing a more or less uneven coating of zinc.

The present invention provides two sets of anodes and pig zinc, one above the other, so that the articles to be coated may be passed between the bodies of zinc and have an even coating deposited thereon without turning the articles.

In the drawings—

Figure 1 is a plan view of part of an electro-galvanizing tank embodying my invention, the vertical separator support being omitted for clearness.

Figure 2 is a longitudinal sectional elevation on the line II—II of Figure 1.

Figure 3 is a transverse sectional elevation taken on the line III—III of Figure 2.

Figure 4 is an enlarged detail view of one of the upper anode members 5 partly in section to show the lead covering.

Referring more particularly to the drawings, the numeral 2 designates the tank body as a whole, which is of standard construction.

A pair of copper bus bars 3 and 4 are mounted along the one side of the tank body.

A plurality of angle iron zinc holders or anodes 5 are supported across the tank in spaced relation with the bottom of the tank. The angle iron holders 5 are covered with sheet or strip lead 6 and form anodes which are adapted to support the pigs of zinc 7, and are connected to the bus bar 3 by copper connectors 8 which are connected to the lead sides 9 of the holders 5.

A plurality of anodes 10, composed of strip lead, are mounted on wood supporting

bases 10* mounted on the wooden spacing strips 11 on the bottom of the tank 2, and are provided with side portions 12 which underlie the side portions 9 of the holders 5 so as to form an electrical connection therewith, and provide for the energizing of the anodes 10 from the bus bar 3. The anodes 10 support a plurality of pigs of zinc 14.

A plurality of cathodes 16 are mounted in the tank 2 and are connected by side members 16* and connectors 17 to the bus bar 4 of opposite polarity from the bus bar 3 so that the circuit may be completed through the electrolytic solution in the tank 2.

Wooden strips 15 are provided along the anode holders 5 to prevent the wire or other articles being coated from striking the lead covering 6 and thereby forming a short circuit which will burn away the lead and expose the iron angles 5 to the action of the electrolytic solution.

A wooden support 19 is secured to the spacing strips 11 to prevent the wire sagging and touching the anodes 10, thus forming a short circuit.

An upper transversely arranged separator support 18 is provided to support vertical separator members 20 which serve to maintain the wires or other articles being coated in transversely spaced relation.

The tank 2 is adapted to be filled with an acid or electrolytic solution of standard composition, and the bus bars 3 and 4 are adapted to be connected to a generator or generators or other source of positive electric current supply.

In operation, the anodes will be energized with the positive current, and the wire or other articles to be electro-plated or electro-galvanized will be energized with the negative current by contact with the cathodes, and passed through the solution in the tank between the anodes 5 and 9, so that the zinc from the pigs carried by the anodes will be deposited evenly on all sides of the articles without the necessity of turning or twisting the articles as they pass through the solution.

I claim—

An electro-plating apparatus comprising an elongated tank, one series of anodes mounted in spaced relation with the bottom of said tank, a second series of anodes mounted in spaced relation above said first named

105

110

series of anodes, a bus bar extending parallel with said tank, means connecting all of said anodes with said bus bar, a second bus bar extending parallel with said tank, a plurality of stationary cathodes mounted in said tank at an elevation intermediate said anodes and adapted to be engaged by the wire or other material being passed between said series of anodes to be plated, means connecting said 10 cathodes with said second named bus bar, wood strips fixedly mounted below said second series of anodes and at least one wood

supporting member fixedly mounted above the upper faces of said second series of anodes to prevent the wire being plated coming into contact with said anodes, and vertically arranged non-conducting separator bars for maintaining a plurality of wires in spaced relation when they are being simultaneously passed through said tank. 15 20

In witness whereof, I have hereunto signed my name.

PETER JEPSEN.
